(57) **CLAIM**

The ornamental design for a speaker box, as shown and described.

DESCRIPTION

FIG. 1 is a front right top perspective view of a speaker box showing my new design;

FIG. 2 is a rear left bottom perspective view thereof;

FIG. 3 is a front elevational view thereof;

FIG. 4 is a rear elevational view thereof;

FIG. 5 is a right side elevational view thereof, a left side elevational view thereof being a mirror image of the right side elevational view;

FIG. 6 is a top plan view thereof; and,

FIG. 7 is a bottom plan view thereof.

The broken away lines in the drawing disclosure indicates indeterminate length of the cable connected to the speaker box, which is not claimed.
